STOCKING AND IMPROVED METHOD OF MANUFACTURING THE SAME

Application filed February 25, 1931. Serial No. 518,092.

Our invention relates to a new and improved stocking, and a new and improved method for manufacturing the same.

One of the objects of our invention is to provide a practical and commercial method for producing a stocking in which the leg of the stocking is made of ravel-resistant material, that is, material which does not run or ravel, in which the stocking is finished by forming the toe section, the heel section, and the underfoot or sole section upon an ordinary hosiery knitting machine of the type which is used for knitting ordinary full-fashioned stockings. The stitches which are produced by the ordinary knitting machine may be designated as "chain" loops.

Another object of our invention is to provide a method whereby the leg blank of a stocking, which has been knitted so as to produce relatively large meshes irrespective of size or quantity in a given area, can be interknit with the toe section, the heel section, and the sole section on knitting machine of any gauge.

Another object of our invention is to provide a method whereby a leg blank which is made of warp-knit fabric can be interknit in a practical and commercial manner with a welt, a heel section, etc., said welt, heel section and the like being formed with chain loops on an ordinary hosiery machine.

Another object of our invention is to provide a stocking of this type, which shall have the appearance of a high priced stocking, and which can be manufactured at greatly reduced cost.

Another object of our invention is to provide a stocking of superior appearance and durability, in which the leg of the stocking is knit so as to have large meshes, the other part of the stocking being made of ordinary knit fabric having chain loops.

Other objects of our invention will be set forth in the following description and drawings which illustrate a preferred embodiment thereof, it being understood that the above general statement of the objects of our invention is intended merely to generally explain the same and not to limit it in any manner.

Fig. 1 is an elevation of a completed stocking made according to our invention, this type of stocking having a type of foot which, with the exception of the toe, is known in the trade as an "English" foot having side seams. 55

Fig. 2 is an enlarged sectional view on the line 2-2 of Fig. 1.

Fig. 3 is a detail elevation showing the flat construction of the lower part of the stocking illustrated in Fig. 1, showing also continuous instep portion, heels and high splicing or reinforcement and without foot bottom or toe. 60

Fig. 4 is a sectional view on the line 4-4 of Fig. 3. 65

Fig. 5 is a sectional view on the line 5-5 of Fig. 1.

Fig. 6 is a diagrammatic view showing how the leg blank is transferred to the needles of an ordinary knitting machine, in order to form the welt section or the like. 70

Fig. 7 is a plan view corresponding to the position of the welt and of the leg blank, which is illustrated in Fig. 8.

Fig. 8 is a view similar to Fig. 6 showing how the welt is originally knitted, independently of the leg blank. 75

Fig. 9 is a view similar to Fig. 8 showing how the tab or end of the leg blank is bent over the welt. 80

Fig. 10 is a plan view showing the welt and the leg blank, in the position illustrated in Fig. 11.

Fig. 11 is a view similar to Fig. 9 showing the next operation in knitting the welt. This figure shows, in dotted lines, how the welt is brought back and is transferred to the needles.

Fig. 12 is a plan view showing the welt and leg blank after the welt has been finished, this view corresponding to Fig. 13.

Fig. 13 is a view similar to Fig. 11 showing how the welt has been doubled in order to form a closed loop, the knitting process having been continued to provide this flat loop with a tab, which is utilized for finishing the welt.

Fig. 14 shows the type of leg blank which is utilized for producing a type of stocking having what is known in the trade as the "French" foot. This figure also shows how

the heel sections are interknit with the leg blank.

Fig. 15 is similar to Fig. 14, save that it illustrates the blank which is utilized for producing that type of stocking having the "English" foot instep.

Fig. 16 shows the type of leg blank which is utilized for producing that type of stocking having the "English" foot, without our 10 improvements.

Fig. 17 illustrates a seamed stocking showing the general appearance of a stocking foot having the "English" type of foot without improvements.

15 Fig. 18 is an end or edge view of Fig. 15.

The silk stockings which are commonly manufactured do not have long life, due to the fact that the leg portion of the stocking is knit with chain loops, so that a broken thread produces "runs" or "ladders."

20 In order to eliminate this objection, it has been proposed to knit the leg portion of a stocking from flat piece goods, such as silk, which have been knit on a warp machine, 25 which is commonly known in the trade as a milanese or tricot machine. This material is also known as glove silk fabric, and it has been largely used for silk underwear and the like.

30 However, it has been very difficult to properly attach to a leg portion made of this material, a welt, a heel, a toe, and underfoot which are made of ordinary fabric having chain stitches, or loops.

35 This has been particularly difficult when the leg portion of the stocking was knit in the form of an open mesh.

According to our invention a stocking of 40 superior appearance, having the leg portion 45 made of open mesh fabric which has been knitted in the flat condition on a milanese or tricot machine, can be readily interknit with the other portions of the stocking, by using the ordinary finishing machines known to the trade, such as the footer, etc., which produce ordinary chain loops.

50 We have illustrated our invention with respect to the manufacture of a fashioned stocking, in which the stocking is first knit and 55 cut in flat shape, and the edges of the blank are then sewed together. However, we do not wish to be limited to any particular type of stocking, and in particular we do not wish to be limited to a stocking in which the leg portion is made of warp-knit fabric.

The leg blank L may be knitted into any 60 suitable shape, depending upon the type of foot which is desired in the completed stocking. For example, the leg blank may have an integral instep portion I and integral heel tabs H. This blank is made of warp-knit fabric, which may have large meshes, so as to present an ornamental appearance.

65 In order to finish the stocking by making the welt and other portions, it is necessary to

use an ordinary knitting machine of fine gauge. If the large meshes of the leg blank L were transferred to the needles of an ordinary knitting machine, each one of the large meshes of the leg blank would be transferred to two or more of the needles of the ordinary knitting machine, so that runs or ladders would be produced, if it was attempted to interknit the leg blank with a welt, or with the heel or the like, in the ordinary manner. We 70 have specifically illustrated the formation of a welt, and it is to be understood that the heel section, the toe section, and the underfoot section can be produced in substantially the same manner.

75 As shown in Fig. 6, after the leg blank has been knit on a flat warp machine and cut into suitable shape, the meshes of the leg blank are transferred to the needles N of an ordinary knitting machine, which is to produce the welt. Each one of the meshes of the leg blank has a number of the needles N passing through the same, and each one of the meshes of the leg blank preferably has the same number of the needles N passing 80 through the same.

85 When the leg blank is so transferred, the major portion of the leg blank is at one side of the needles N, and a tab or end portion 1 of the leg blank is at the other side of the 90 needles N.

95 The leg blank is so transferred as to be below the sinkers S and also below the knocking-over bits K so that the knitting machine can operate without operating upon the leg 100 blank L.

When the leg blank has been so transferred, as shown in Fig. 6, the knitting of the welt W is started in the usual manner, the ordinary 105 welt hooks 10 being utilized. This step is shown in Fig. 8.

When a sufficient length of the welt has been knitted, the tab or end 1 of the leg blank is passed over the beards of the needles N in such a manner that no fabric is left on the back of the needles, each large mesh being passed over and between the needles to the front and above the partly knitted welt shown in Fig. 9. That is, if the welt fabric was not already on the needles, the large mesh fabric, due to the turning over the tab would be completely removed from the needles. This cannot happen because the mesh fabric, while it actually comes off clear from the needles, is retained by the welt fabric and is not either 11 under the needle beards or in contact with the needles after having been turned back. Referring to the large open mesh it will be noticed that the large loops or meshes are 11 interlinked with the loops of the welt and the entire leg of the stocking is suspended by this linking of the large loops into the small loops, the large mesh linking into and between a multiple of the smaller welt fabric loops. In actual practice the leg is not knitted 12

on to the welt by having stitches or loops drawn through it in the ordinary knitting process, but by a locking of the large mesh into the small mesh fabric. After the parts are in the position shown in Fig. 9, the knitting of the welt causes its loops to pass through and interlink with the meshes of the leg blank, without binding the interlinked loops to each other. In the completed stocking the leg is interlinked with the welt intermediate the ends of the welt, and at a part of the welt where the loops of the welt comprise a single continuous series formed by the operation of knitting the welt.

The leg blank is now held in the operative position, and the knitting operation is then continued so that the tab or end 1 (which may be very short) is interlocked and suspended in the fine chain stitches of the welt W. A picot edge is formed along the line 11.

When a suitable length of the welt has been knitted, the outer loops of the welt are released from the welt hooks 10, and these outer loops are then transferred to the needles N, 25 this being indicated in dotted lines in Fig. 11.

The knitting operation is then continued as shown in Fig. 13, so as to produce a closed loop commonly known as a welt having a tab or extension 12. This tab or extension 12 is then looped close to the inner surface of the welt along the line 14 with a lock stitch looper. Hence, and as shown in Fig. 2, the welt comprises a flat closed loop made of fine chain 30 stitches, and interlocked with the top of the leg blank, the top of the leg blank being located between the interior walls of said flat loop. Likewise, when the stocking is completed, the finish of the welt is invisible from 35 the exterior of the stocking. Such a tab as is needed to make a looping course for a completed finished welt is not necessary on hosiery welts when the welt is at the beginning of a stocking, as in the ordinary process of making 40 full-fashioned hosiery, for in that case where the welt is made first the entire stocking leg takes the place of the tab and is looped off at heel and toe. But in the case when the stocking is made upside down and the welt at 45 50 the latter end, such a looping off tab is necessary. We have so placed this tab as to hide the looping off from being conspicuously shown where the attachment of the welt and leg blank is suspended.

The same general method is utilized for forming the other sections which are to be interknit with the leg blank.

For example, and as shown in Fig. 5, the toe section T of the stocking includes a flat 55 60 loop having walls 8 and 9, which enclose a tab or end 7 of the leg blank L. The end of the leg blank is locked and suspended in substantially the same manner as the welt. This tab is made as short as possible.

Likewise each heel portion H of the stock-

ing is provided with a loop having walls 5 and 6, these walls being suspended from leg blank L, its meshes interlocking in the flat loop substantially in the same manner as the welt and toe.

It is therefore possible to take a leg blank L made of warp-knit fabric, and to easily and firmly interknit or suspend the same with the other sections of the stocking, thus providing a handsome stocking of expensive and ornamental appearance, and at a greatly reduced cost.

As shown in Fig. 2, the welt of the stocking is finished above the top of the upper end 1 of the leg blank L. For convenience, the type of knit fabric which is used for making the leg of the stocking may be designated as "open-mesh" fabric, because the meshes are readily visible, instead of being practically invisible as in the case of fabric which is knitted upon a fine gauge machine. This fabric may be any tricot fabric, or any milanese fabric, without departing from the invention.

While we have shown a preferred method of making the improved stocking, we do not wish to be limited to any particular method of making the same. It will be noted that the loops of the leg blanks and the loops of the supplemental stocking section are inter-linked, instead of being interknit. When the term "interlinked" is used in the claims, we intend to exclude a stocking in which the parts of the stocking which are referred to in said claims are interknit. The improved stocking has the loops of the sections intermeshed without binding them to each other, as said binding, which would result from ordinary interknitting, would be objectionable because it would require additional non-raveling stitches and an objectionable bulge would be produced at the line of intersection.

Likewise, we do not wish to be limited to any size of mesh opening or to any particular mesh pattern, and the invention also includes plain tricot or milanese fabrics, or any other fabric. That is, many features of the invention are applicable to a stocking having a leg made of chain-loop knitted fabric of the ordinary kind. For convenience, the opening of the leg blank may be referred to either as meshes or loops. When we refer to "loops" in the claims, we intend to include a warp-knit fabric as well as ordinary knit fabric having chain-loops.

Likewise, while we have shown a preferred embodiment of our invention, it is obvious that numerous changes and omissions could be made without departing from its spirit.

We claim:

1. A method of connecting the leg blank of a stocking to the welt portion thereof, which consists in knitting said welt section in the form of a loop which encloses and is interknit with the upper end of the leg blank,

and also forming said loop with a tab, and connecting said tab to the welt at the inner wall of said welt.

2. A method of connecting a knitted leg blank of a stocking to another section of said stocking, which consists in transferring the knitted leg blank to the needles of a knitting machine, so that the major portion of said leg blank is on one side of said needles, and the 10 end portion of said leg blank is on the other side of said needles, knitting said section on said needles wholly separated from said leg blank, passing the end of the leg blank over the ends of said needles, so that the end of 15 said leg blank overlies the knitted section, and transferring the outer loops of said knitted section to said needles to form a closed interknitted loop which is interknit with the end of said leg blank.
- 20 3. A method of connecting a knit leg blank of a stocking to another section of said stocking, which consists in transferring the knitted leg blank to the needles of a knitting machine, so that the major portion of said leg blank is 25 on one side of the said needles, and the end portion of said leg blank is on the other side of said needles, knitting said section on said needles wholly separated from said leg blank, passing the end of the leg blank over 30 the ends of said needles, so that the end of said leg blank overlies the knitted section, transferring the outer loops of said knitted section to said needles to form a closed interknitted loop which is interknit with the end of said 35 leg blank, and continuing the knitting operation by means of said needles to form said loop with a tab.

4. An improved stocking comprising a leg section of warp-knit open mesh fabric having 40 a stocking-section connected to one end thereof, said stocking-section consisting of a knitted loop which encloses and which is interknit with the adjacent end portion of said leg section, said stocking-section being knit 45 with chain loops and having a closer mesh than said leg section.

5. A method of forming a stocking having a leg blank of knit material, and a stocking section which is formed of knit material and 50 which is connected to said leg blank, which consists in knitting said stocking section so as to increase its length after knitting its loops so that they extend through the loops 55 of said leg blank intermediate the ends of said leg blank, and the loops of said leg blank and of said section are loosely inter-linked.

6. A method of forming a stocking having 60 a leg blank made of knit material, and having a stocking section which is made of knit material and which is connected to said leg blank, which consists in knitting said stocking section with a double wall, and inter- 65 linking the loops of only one of said double

walls with the loops of the leg blank, intermediate the ends of said leg blank.

7. A method of forming a stocking having a leg blank made of knit material, and a stocking section which is connected to said leg blank, said stocking section being also made of knit material, which consists in knitting said stocking section with double walls, interlinking said stocking-section with the leg blank intermediate the ends of the leg blank, 70 and finishing the stocking section to form a loop by connecting its ends together at a point which is spaced from the line of intersection between said loop and the leg blank. 75

8. An improved stocking comprising a leg section made of knit material, and a stocking section made of knit material, the loops of the stocking section being interlinked with the loops of the leg section intermediate the 80 ends of the leg section, said stocking section 85 consisting of a knitted fabric loop having its ends connected to each other, the line of said connection being spaced from the line of intersection between said section and said leg blank. 90

9. An improved stocking comprising a leg section made of warp-knit material and having a stocking section made of chain-loop knitted material connected thereto intermediate the ends of said leg section, the loops of said leg section passing through the loops of the stocking section intermediate the ends of said leg section, the interlinked loops having a relative free movement with respect to 95 each other. 105

In testimony whereof we affix our signatures.
